UNITED STATES PATENT OFFICE.

JOHN J. HARTEN, OF HARTFORD, AND MALCOLM H. AMES, OF WEST HARTFORD, CONNECTICUT, ASSIGNEES TO PRATT & WHITNEY COMPANY, OF NEW YORK, N. Y., A CORPORATION OF NEW JERSEY.

TAILSTOCK CENTER LUBRICATOR.

Application filed October 24, 1924. Serial No. 745,628.

This invention relates to lathes and particularly to a lathe of the automatic type in which blanks are automatically fed to a supporting and rotating position and operated upon by a suitable cutting tool.

More particularly, the present invention relates to a means for supplying lubricant to the tailstock center and which is adapted to be actuated with each movement of the tailstock spindle into its operative position.

Another object of the present invention is to provide automatic means adapted to actuate a small pump mounted on a fixed part of the automatic lathe and adapted to force a small quantity of lubricant directly to the center supporting one end of the work being operated upon.

One feature which enables us to accomplish the above named object is that we mount a container for the lubricant upon the lathe and in its lower portion provide a pump, the plunger of which is actuated in timed relation to the movements of the tailstock spindle and preferably by lever controlling movements of the tailstock spindle. With each movement of the plunger a small amount of lubricant is admitted to the tailstock center through a suitable flexible conduit.

Another feature which is advantageous is that we actuate the pump plunger by means of a supplementary lever actuated by the cam and lever by means of which movements of the tailstock spindle are controlled.

With these and other objects in view, our invention consists in the features of construction and operation set forth in the following specification and illustrated in the accompanying drawing.

In the accompanying drawing annexed hereto and forming a part of this specification, we have shown our invention embodied in a special form of automatic lathe but it will be understood that the invention can be otherwise embodied and that the drawing is not to be construed as defining or limiting the scope of the invention, the claims appended to this specification being relied upon for that purpose.

In the drawing:

Figure 1 is a rear elevation of a portion of an automatic lathe having my present invention applied thereto.

Fig. 2 is a detail sectional view upon an

enlarged scale of the conduits for admitting the lubricant to the tailstock center.

Fig. 3 is a detail view of the tailstock center shown in section to show the oil admitting conduits, and

Fig. 4 is a section upon an enlarged scale of the pump.

In the above mentioned drawing, we have shown but one embodiment of the invention which is now deemed preferable but it is to be understood that changes and modifications may be made within the scope of the appended claims without departing from the spirit of the invention.

Briefly, and in its broadest aspect, our invention consists in the following principal parts: first, an automatic lathe having tailstock actuating mechanism operated by a suitable cam mounted upon a main cam shaft; second, a lubricant container having a pump mounted preferably in its lower portion; third, a pump plunger actuated by a lever connected to and operated by the tailstock operating cam; fourth, a flexible conduit extending from the lubricant pump to the tailstock center; and fifth, passages in said center to permit the lubricant to be conveyed to the work bearing portion of the center.

Referring more in detail to the figures of the drawing, we provide upon the base or bed 10 of an automatic lathe a lubricant container 11 preferably permanently bolted directly to a surface upon the upper and rear portions of the bed. Within this lubricant container 11 is provided a pump having a pump plunger 12 actuated axially by a suitable lever 13. In order to actuate this lever 13 in timed relation to the movement of the tailstock spindle 14 and other automatically actuated mechanisms on the machine, we attach the lever 13 to an oscillating shaft 15 having an arm 16 extending downwardly to engage one of the cams on a main cam shaft 17. Preferably, and as shown in the drawing, this cam shaft 17 is provided at one end with a wheel 18 having cam strips 19 attached to its periphery. These cam strips 19 are adapted to oscillate the depending arm 16 and therefore oscillate the short traverse shaft 15 connected to the pump operating plunger 12. As the pump plunger 12 is adapted to force lubricant to the tailstock center 28 with each

movement of its spindle 14, we make use of the same cam to operate the lubricant pump plunger 12 as is used to actuate the tailstock spindle 14. From the above it will be seen that with two opposed cam strips as shown the lever 16 and consequently the plunger 12 will be moved forward and backward during each rotation of the shaft 17, and simultaneously with movements of the spindle 14.

The lubricant pump above referred to comprises a bushing 20 into which the pump plunger 12 enters and, in order to provide a pump of simple design, the plunger 12 is provided with a reduced portion 21 which passes entirely through the pump bushing 20. By means of a packing gland 22 this sliding joint may be maintained pressure tight. Also the pump plunger 12 is provided with an intermediate reduced portion 22 which at each reciprocation of the pump plunger 12 moves from a point outside the pump bushing 20 to the position within shown in full lines. It will be seen therefore that with each movement of the pump plunger 12 toward the left, lubricant will enter the space within the pump bushing and that, as soon as the intermediate reduced portion 23 of the pump plunger 12 enters the bushing 20, this oil will be forced outwardly through the conduit 24 as shown. In order to prevent retrograde movement of the oil within the body of the pump on the movement of the plunger 12 to the left, a check valve 25 is provided in the form of a spring pressed ball.

Connected directly to the discharge conduit 24 of the pump is a flexible conduit 26 extending to a fixture 27 secured to a part of the tail stock center 28. This fixture 27 is provided with a passage 29 extending therethrough which admits the lubricant to the axis of the tailstock center 28 through a suitable passage 30 joining that within the fixture 27. Extending axially within the center 28 is a suitably bored passage 31, suitably plugged at its outer end and provided with a branch conduit 32 permitting the lubricant to pass through the center 28 and laterally outward. A channel or groove

33 provided in the periphery of the center permits the lubricant to pass to the work engaging surface of the center. From this point the lubricant spreads down over the conical point of the center 28 so that this surface will be fully lubricated each time a work piece is mounted thereon and the tailstock spindle moved to operative position.

What we claim is:

1. A lubricant supplying means for the tailstock center of an automatic lathe comprising in combination, a lubricant container, a pump associated therewith, a pump plunger therein, a conduit from said pump to the center on a tailstock spindle, a main cam shaft, actuating means thereon for said tailstock spindle, and supplementary means movable with said actuating means for said spindle to reciprocate said pump plunger.

2. A lubricant supplying means for the tailstock center of an automatic lathe comprising in combination, a lubricant container adapted to be secured to a fixed portion of the lathe, a pump associated therewith, a pump plunger therein, a conduit from said pump to said tailstock center, a main cam shaft, actuating means thereon for said tailstock spindle, and supplementary means movable with said actuating means for said spindle to reciprocate said pump plunger to advance lubricant to said tailstock center simultaneously with movement of said center into operative position.

3. A lubricant supplying means for the tailstock center of an automatic lathe comprising in combination, a lubricant container, a pump associated therewith, a pump plunger therein, a flexible conduit from said pump to the tailstock center on a tailstock spindle, a main cam shaft, cam actuating means thereon for said tailstock spindle, an oscillatory lever attached to said plunger, and means movable simultaneously with said actuating means for said tailstock to oscillate said lever and reciprocate said pump plunger.

In testimony whereof, we hereto affix our signatures.

JOHN J. HARTEN.
MALCOLM H. AMES.
